UNITED STATES PATENT OFFICE.

KENNETH B. NOBLE, OF HARTFORD, CONNECTICUT, ASSIGNOR TO THE A. C. GILBERT COMPANY, OF NEW HAVEN, CONNECTICUT, A CORPORATION OF CONNECTICUT.

GOVERNOR FOR MOTORS.

Application filed June 5, 1925. Serial No. 35,196.

My invention relates to the class of devices that are employed to regulate or govern the speed of motors, and an object of my invention, among others, is the production of a 5 governor that is simple in construction and that is especially effective in operation.

One form of device embodying my invention and in the construction and use of which the objects herein set out, as well as others, 10 may be attained, is illustrated in the accompanying drawings, in which—

Figure 1 is a view in side elevation of a portion of a motor illustrating my improved 15 governor attached thereto, the latter being shown in central longitudinal section, on a plane passing through the pivots of the counterweights and axis of the shaft.

Figure 2 is a view in cross section through the governor showing the braking members 20 in inoperative position.

Figure 3 is a similar view but showing the braking elements in action.

While my invention is not limited in its use to a motor of any special construction, 25 yet as I have produced it especially for employment in connection with an electric motor such has been selected by me for the purpose of illustrating my invention in the drawings herein, in which the numeral 5 indicates a motor, a portion only of which is shown, having the usual hub 6 with a shaft 7 projecting from within the case through said hub, in a manner common to structures of this class.

35 My improved governor comprises a stationary cylindrical housing that may be secured to said hub, or that may be otherwise suitably secured in place so long as its inner surface is concentric with the shaft 7. The 40 inside of the housing is formed to present a smooth, finished surface against which a braking pressure is exerted by the centrifugal action of the counterweights 9, preferably two in number, that are supported by 45 the shaft 7.

In the preferred form of construction, and as shown herein, these weights are pivotally attached to a disc 10 secured to the shaft 7, and this disc, if desired, may be in the form 50 of a pulley or sheave employed for the purpose of driving other and auxiliary devices. Each counterweight may be mounted for pivotal action upon a screw pin 11 projecting from the side face of the disc 10, and its 55 centrifugal action is limited and controlled by

the tension of a spring 12 in the form of a split ring that is secured, as by means of a shouldered pin 13, to said weight at a distance from its pivot. Any suitable kind of a spring may be employed, in the structure 60 herein shown a single spring being secured to both weights toward that end of each opposite the hinge pin.

The outer surface of the counterweights are preferably equipped with felt or other 65 proper friction material 14 to effect the desired braking pressure against the inner surface of the stationary housing 8, the centrifugal action of the weights being limited and controlled by the tension of the spring which 70 may be such as to suit the purpose for which the motor is especially designed.

In the operation of the governor, as the motor speed increases under idle load the 75 weights 9 are correspondingly thrown out by centrifugal action effecting a braking force against the housing 8, the amount of pressure caused by this centrifugal action being determined by the limit tension of the springs connected with said weights. For example, 80 when the motor is operating under load with the speed below the maximum control rating the weights do not function, and the motor operates as if the governor were not in place. The instant, however, that the load is removed and the motor commences to race 85 under idle conditions, the governor promptly acts to set up its control and by its braking action prevents excessive speed of the motor, the former condition being illustrated in 90 Figure 2 and the latter condition in Figure 3.

It is essential that in electric motors particularly the shafts shall be free to "float" 95 endwise, and it is to be noted that the governor illustrated and described herein is so constructed and applied as to permit this free floating of the armature shaft.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A governor comprising a housing and a 110

motor shaft relatively movable, a plurality of counterweights supported and relatively movable with respect to said shaft and adapted to make contact with said housing 5 substantially entirely around its inner surface, and a single resilient split ring secured at different points thereon to said weights to control the action of the latter under centrifugal force.

2: A governor comprising a housing and a 10 motor shaft relatively movable, a plurality of counterweights supported and relatively movable with respect to said shaft, and a single resilient split ring supported by and secured to all of said counterweights to control the action thereof under centrifugal force. 15

KENNETH B. NOBLE.
